UNITED STATES PATENT OFFICE

WILLIAM A. SMITH, SR., OF EASTON, PENNSYLVANIA, ASSIGNOR TO INGERSOLL-RAND COMPANY, OF JERSEY CITY, NEW JERSEY, A CORPORATION OF NEW JERSEY

OILING DEVICE

Application filed April 29, 1932. Serial No. 608,224.

This invention relates to rock drills, but more particularly to an oiling device for rock drills of the fluid actuated type equipped with a feeding screw which threadedly engages the rock drill or an element carried thereby for actuating the rock drill to and from the work.

One object of the invention is to assure an ample supply of lubricant to the cooperating surfaces of the feed screw and the element which it engages.

Other objects will be in part obvious and in part pointed out hereinafter.

The accompanying drawing is a longitudinal sectional elevation of a rock drill and its feed screw having the invention applied thereto.

Referring more particularly to the drawing, A designates a rock drill comprising a cylinder B having front and back heads C and D respectively which may be secured to the cylinder B in any well known manner.

Within the cylinder is a piston chamber E having a free exhaust port F which is controlled by the head G of a piston H reciprocable within the piston chamber E.

As is customary in apparatus of this character, the front head C serves as a housing for chuck mechanism J into which extends a working implement K to receive the blows of the hammer piston H. The rear end of the chuck mechanism J is journaled within an extension L of a bushing O which extends into the cylinder B to form a closure for the front end of the piston chamber E.

In the periphery of the bushing O is an annular recess P which serves as a reservoir for oil whereby the cooperating movable and stationary surfaces of the various elements of the rock drills are lubricated. The cylinder B may, as shown, serve as an outer bounding surface for the reservoir P and in the wall of the cylinder is an aperture Q through which oil may be introduced into the reservoir P. The aperture Q is normally sealed by a filler plug R threaded thereinto.

Rearwardly of the piston chamber E and in the cylinder B is an enlarged bore S to accommodate valve and rotation mechanisms T and U, respectively. The valve mechanism

T, which is disposed adjacent the rear end of the piston chamber E to form a closure therefor, comprises a pair of plates V and W, and in the plate W is a valve chamber X to accommodate a distributing valve Y of the oscillatory plate type having wings Z and b for controlling front and rear inlet passages c and d, respectively. The rear inlet passage d is located entirely within the plate V and opens directly into the rear end of the piston chamber E and the front inlet passage c extends through the plate V and through the cylinder B to the front end of the piston chamber E.

The rotation mechanism U, which is shown as being of a well known type, comprises a ratchet ring e interposed between the plate W and the back head D. Within the ratchet ring e is a head f of a rifle bar g which extends through the valve mechanism T and is interlockingly engaged with the piston H in a well known manner. The head f of the rifle bar is shown provided with the usual pawls h for engagement with the ratchet ring e to effect rotary movement of the working implement K through the piston H and the chuck mechanism J, to which the piston may be interlockingly connected.

The admission of pressure fluid into the rock drill is controlled by a throttle valve j which may be in constant communication with a source of pressure fluid supply and controls a supply passage k extending from the throttle valve j to the valve chamber X.

The oil within the reservoir P is constantly subjected to pressure fluid which may be conveyed to the reservoir by a passage o in the cylinder B and which passage opens into the supply passage k, or to some other suitable source of supply to assure the presence of pressure fluid within the passage o during the operation of the rock drill. In the periphery of the bushing O and at points on opposite sides of the reservoir P are annular grooves p and q which communicate with the passage o through passages r in the wall of the cylinder B. The pressure fluid is conveyed from the grooves p and q into the reservoir P by passages s in the bushing O.

The manner in which the oil is forced from

the reservoir P to be delivered to the various movable parts of the rock drill is substantially like that disclosed in United States Patent No. 1,789,117 granted to William A. Smith, January 13, 1931, that is, the oil passes from the reservoir through restricted clearance spaces *t* between the periphery of the bushing O and the wall of the cylinder B, both in forwardly and rearwardly directions into annular grooves *u* located in the periphery of the bushing O.

As in the aforesaid patent, the cylinder B has an oil conveying passage *v* which communicates with a groove, or both grooves *u*, through passages *w*. Near the rear end of the passage *v* is a passage *x* which leads through the cylinder B and the plate V to a bore *y* in the plate V and through which the rifle bar *g* extends.

20 In the operation of the device so far described pressure fluid admitted into the passage *o* flows through the associated passages into the reservoir P. Such pressure fluid forces oil forwardly and rearwardly from the reservoir P through the restricted spaces *t* into the groove *u*. Inasmuch as the passage *v* is in communication with the rear end of the piston chamber E through the passage *x* and the bore *y*, pressure fluid flows into the passage *v* during each admission of pressure fluid into the rear end of the piston chamber.

30 The pressure fluid in the passage *v* again returns to the piston chamber when the piston head G uncovers the exhaust port F to communicate the rear end of the piston chamber with the atmosphere. The oil entrained in the pressure fluid flowing from the passage *v* will then be deposited upon the rifle bar *g* and such other elements to which the pressure fluid previously stored in the passage *v* has access.

40 In accordance with the present invention it is contemplated to utilize a portion of the oil conveyed by the pressure fluid passing through the passage *v* for lubricating the feeding means whereby the rock drill is actuated to and from the work, as for instance, that designated by *z* and comprising a feed nut 2 disposed within a bore 3 of a lug 4 on the cylinder B. The feed nut 2, which may be of a well known type, has a threaded aperture 5 that extends entirely through the feed nut. On one end of the feed nut is a head 6 that seats against an end surface 7 of the lug 4. The opposite end of the feed nut projects rearwardly of the lug 4 and is provided with threads 8 for the accommodation of a nut 9 which seats against the rear end of the lug 4 to hold the feed nut 2 fixedly within the lug 4.

50 To the end that the cooperating surfaces, that is, the threads of the feed screw *z* and the feed nut 2 may be adequately lubricated the feed nut is provided with a radial passage or passages 10 that communicate at one

end with the interior of the nut 2 and open with their other ends into an annular groove 11 in the periphery of the nut 2. In the wall of the cylinder B is a passage 12 to afford communication between the annular groove 11 and the passage *v*.

60 Preferably the passages 10 open into the interior of the feed nut at points about midway between its ends thereby preventing undue loss of pressure fluid and the violent 75 expulsion of lubricant from the ends of the nut.

In practice, upon each exhaust of pressure fluid from the passage *v* a portion of such pressure fluid, together with the oil carried thereby, flows into the feed nut 2 where the oil is deposited upon the cooperating surfaces of the feed nut and the feed screw *z*. These surfaces of the feed nut and the feed screw will therefore be well lubricated to protect them against wear and the connection between the feed screw and the feed nut may be made initially tighter than heretofore.

I claim:

1. In a fluid actuated rock drill, the combination of a casing and feeding means carried by the casing and comprising a pair of members in threaded engagement with each other, and a passage in the casing and one of the members for conveying oil from a source of supply directly to the cooperating surfaces of the members.

2. In a fluid actuated rock drill, the combination of a casing and a feed nut carried by the casing, a feed screw in threaded engagement with the feed nut, a member in the rock drill having a reservoir for oil, and a passage in the casing and the feed nut for conveying oil from the reservoir to the cooperating surfaces of the feed nut and the feed screw.

3. In a fluid actuated rock drill, the combination of a casing and a feed nut carried by the casing, a feed screw in threaded engagement with the feed nut, a member in the rock drill having a reservoir for oil, and a passage in the casing and the feed nut for conveying oil from the reservoir to the cooperating surfaces of the feed nut and the feed screw and opening into the feed nut at a point intermediate the ends of said feed nut.

In testimony whereof I have signed this specification.

WILLIAM A. SMITH, SR.
